(57) **CLAIM**

We claim the ornamental design for a folded container, as shown and described.

DESCRIPTION

FIG. 1 is a front perspective view of an embodiment of the claimed design;

FIG. 2 is a front view of the embodiment of FIG. 1;

FIG. 3 is a rear view of the embodiment of FIG. 1;

FIG. 4 is a top view of the embodiment of FIG. 1;

FIG. 5 is a bottom view of the embodiment of FIG. 1;

FIG. 6 is a right side view of the embodiment of FIG. 1; and,

FIG. 7 is a left side view of the embodiment of FIG. 1.

The ornamental design which is claimed is shown in solid lines in the drawings. The broken lines in the drawings are for illustrative purposes only and form no part of the claimed design.

1 Claim, 5 Drawing Sheets
